(57) **CLAIM**

We claim the ornamental design for a holder for a chromatography column, as shown and described.

DESCRIPTION

FIG. 1 is a bottom perspective view of a first version of a holder for a chromatography column with dashed lines that represent an unclaimed environment.

FIG. 2 is the bottom perspective view of the first version of the holder for a chromatography column shown at a reduced scale.

FIG. 3 is a top perspective view of the first version of the holder for a chromatography column shown at a reduced scale.

FIG. 4 is a front elevational view of the first version of the holder for a chromatography column, the rear elevational view is identical thereto.

FIG. 5 is a right side elevational view of the first version of the holder for a chromatography column, the left side elevational view is identical thereto.

FIG. 6 is a top plan view of the first version of the holder for a chromatography column.

FIG. 7 is a bottom plan view of the first version of the holder for a chromatography column.

FIG. 8 is the bottom perspective view of a second version of the holder for a chromatography column shown at a reduced scale.

FIG. 9 is a top perspective view of the second version of the holder for a chromatography column shown at a reduced scale.

FIG. 10 is a front elevational view of the second version of the holder for a chromatography column, the rear elevational view is identical thereto.

FIG. 11 is a right side elevational view of the second version of the holder for a chromatography column, the left side elevational view is identical thereto.

FIG. 12 is a top plan view of the second version of the holder for a chromatography column; and,

FIG. 13 is a bottom plan view of the second version of the holder for a chromatography column.

The broken line showing in FIG. 1 is included for the purpose of illustrating environmental structure and forms no part of the claimed design.
